STEPHEN CHESTER AND OTTO BÜRSTENBINDER, OF NEW YORK, N. Y.

Letters Patent No. 85,906, dated January 19, 1869.

IMPROVED METHOD OF PREPARING NITRO-GLYCERINE.

The Schedule referred to in these Letters Patent and making part of the same.

To all whom it may concern:

Be it known that we, STEPHEN CHESTER and OTTO BÜRSTENBINDER, both of the city and State of New York, have invented a new and improved Method of Producing Nitro-Glycerine; and we do hereby declare that the following is a full and exact description thereof, reference being had to the accompanying drawings, and to the letters of reference marked thereon.

Figure 1 is a perspective view of the entire apparatus used for combining the glycerine-oil with the compounded nitric and sulphuric acids, in which—

a represents a revolving table, upon which a vessel, *b*, is placed, containing the acids already mixed in the requisite proportions.

On the shelf *c*, above this vessel, is placed another vessel, *d*, containing the glycerine-oil, from which a pipe with stop-cock, *e*, leads, so as to let the oil drop or flow into the mixture of acid at pleasure, the rapidity of flow being governed by the stop-cock.

Within the glass or other vessel containing the acids is suspended a glass tube, *k*, with branches, (which apparatus is more particularly delineated in Figure 2.)

This consists of a main perpendicular tube, terminating in a fine perforated point, with several radial branches, extending in several horizontal planes, and of diverse lengths, but all terminating in fine perforated points, but all being bent in the same direction, to the right or to the left, as the case may be, so that the axis of the small aperture shall be tangential to the arc described by its respective tube, the axis of the main perpendicular tube being the centre, so that if gas or air were forced through the main tube, escaping through the several apertures described, the entire apparatus would have a tendency to revolve in the direction opposite to those in which the minute jets escaped.

This apparatus being, as before described, suspended in the mixing-vessel *b*, is connected with a tube and stop-cock, *f*, with a gasometer, *G*, containing carbonic-acid gas.

A small ice-box, in which is a "worm," may be inserted between the glass apparatus and gasometer, so that the gas, in its passage through the worm, may be made colder in its passage, but this is not an essential feature in the invention.

It is evident that if the stop-cock *f* be opened after the above-described arrangements have been completed, and the glass apparatus *k* be restrained from revolving, the escape of gas from the several apertures will cause the fluid to rotate, and that part of the vessel not already filled with liquid will be occupied by the carbonic-acid gas, to the exclusion of atmospheric air; also that the minute bubbles of gas, permeating every part of the mixture, will rapidly convey away the heat that may be caused by chemical action.

But great heat is caused by the union of the glycer-

ine-oil with the mixture of acids. Hence it appears that the temperature of the compound, whilst the oil is being introduced, can be almost exactly regulated by closing, partially, the one stop-cock, and opening the other, so as to allow the gas or the oil to flow more rapidly, as the thermometer *h*, suspended in the mixing-vessel, indicated that the temperature of the fluid was rising above or falling below the point at which experience has shown that the desired chemical union takes place.

As combustion very quickly takes place if the temperature be allowed to rise much above 65° Fahrenheit, and the oil and acids do not readily unite if the temperature be below 60°, it is highly important that the means of regulating the temperature should be controllable and instant in their effects.

The revolving table, before described, permits a more rapid rotation to be given to the mixture, if desirable, if, for the purpose of allowing the temperature to rise, the flow of gas be checked partially, so that the rotation of the liquid produced, as first described, becomes sluggish.

The rapidity with which heat is conveyed away from the mixture by the expansion of cold compressed carbonic-acid gas within the liquid, renders it possible to introduce the oil very rapidly, as compared with any other known process, and the ease with which the temperature is controlled, enables the operator to manipulate several apparatus.

But, additional to the advantages above claimed for the use of carbonic-acid gas, it is found that, on account of the acids and air being separated by a superincumbent atmosphere of carbonic-acid gas, the absorption of water from the atmosphere by the sulphuric acid is prevented, and also the evaporation of the acids, that would take place when compressed air forced through the mixture, and in consequence, a greater product is obtained.

It is now believed, with a certain amount of ingredients used, that the product obtained by this process is twenty per cent. greater than that produced by any other process.

As the method of separating the blasting-oil from the mixture of acids and oil by washing in water is common to all methods of manufacture, and forms no part of what we claim as novel in our method of manufacture, we do not deem it necessary to describe that portion of the process particularly.

We believe and claim, however, that a small portable table, containing several of the apparatus above described, with one small cylinder of carbonic-acid gas, comprising, altogether, an apparatus that can easily be carried by two men, is capable of mixing the ingredients for producing one hundred pounds of nitro-glycerine per day, and no other apparatus is required to complete the operation, and produce the pure blasting-

oil, than the necessary stone or other vessels to contain the above-described mixture and the quantity of water required.

Hence, the oil can be produced in all reasonable quantities, wherever it may be required, without danger in its manufacture, and thus avoiding transportation, handling, or packing.

Claims.

1. We claim the mixing of the ingredients from which explosive oil is produced, under an atmosphere of carbonic-acid gas.

2. We claim the cooling of mixtures producing explosive oil or fluid, by the ebullition of cool compressed carbonic-acid gas through the mixture or liquid.

3. We do not claim the stirring of fluids by the ebullition of air or gases forced through tubes therein, but we do claim the method of causing the liquid to rotate by means of the escape of jets of gas, substantially in the manner and for the purposes described.

4. We claim the arrangement of mixing-vessels,

glass tubes, with apertures, as described, in connection with table, gasometer, flexible tubes, stop-cocks, thermometer, frame, oil-vessel, &c., in one portable apparatus, substantially in the manner and for the purposes described.

5. We claim the mixing of the ingredients producing explosive mixtures, under an atmosphere which does not support combustion, and through which no external cause of deflagration is liable to reach the mixture.

6. We claim broadly the use of carbonic-acid gas, as an agent in the production of explosive fluids or mixtures.

7. We claim the production of an explosive compound, other than the nitro-glycerine, (so called,) made without the combination of carbonic-acid gas with other ingredients.
